DECORATIVE PLAQUE FOR A BUTTSTOCK OF A FIREARM

Ewald F. Nickel, New Haven, Conn., assignor to The Marlin Firearms Company, a corporation of Connecticut

Filed July 1, 1969, Ser. No. 18,005

Term of patent 14 years

Int. Cl. D22—02

U.S. Cl. D22—7

FIG. 1 is a side view of a decorative plaque for a buttstock showing my new design;

FIG. 2 is an enlarged fragmentary section taken on the line 2—2 of FIG. 1.

The buttstock is shown in broken lines in FIG. 1 for illustrative purposes only.

I claim:

The ornamental design for a decorative plaque for a buttstock of a firearm, as shown and described.
